UNITED STATES PATENT OFFICE.

WILLIAM TEMPLIN, OF CHICAGO, ILLINOIS.

TIE-SLIDE.

No. 874,456.

Specification of Letters Patent.

Patented Dec. 24, 1907.

Application filed January 28, 1907. Serial No. 354,457.

To all whom it may concern:

Be it known that I, WILLIAM TEMPLIN, a citizen of the United States, residing at Chicago, in the county of Cook and State of Illinois, have invented a certain new and useful Improvement in Tie-Slides, of which the following is a specification.

My invention relates to tie slides and it is illustrated in the accompanying drawings 10 wherein

Figure 1 is a front view of the slide in position on a section of a collar. Fig. 2 is a section on the line 2—2 of Fig. 1. Fig. 3 is a detail showing the adjustable sliding collar 15 clamp.

Like parts are indicated by the same letter in all the figures.

A is a portion of a collar and B a portion of a tie, parts of which are broken away.

20 C is the shirt button which projects through the button hole D, both shown in dotted lines underneath the tie.

E is a lower curved branch and F an upper straight branch of the frame which comprises 25 the vertical portion G with the curved parts H, J.

K is a roller mounted in the two ends of the parts E and F.

L is the lower upwardly curved end of the 30 collar clamp preferably of elastic or yielding material on the slide N which is slidably supported on the part G.

The use and operation of my invention are as follows: The device is intended to be used 35 in connection with a collar, and particularly a turndown collar, for the purpose of keeping the tie free from the collar button and permitting it to slide easily. The tie is passed through the slide between the body portion 40 G and the parts H, J, being inserted through the opening between the last two parts. It lies across the roller and when the slide is in position on the collar where it is held by the collar clamp, with the button lying between 45 the four parts of the slide, the tie is held to a degree away from or at least is prevented from bearing altogether upon the head of the button. The sliding motion of the tie is facilitated by the roller. The two folded down 50 ends with the associated frame piece constitute a holder through which the tie passes. The frame of the slide is here shown as substantially rectangular and open in the mid-

dle. The roller K with its shaft is, in effect, a connecting piece between the two ends of 55 the slide frame.

I claim:

1. In a tie slide the combination of a frame detachably secured to the collar and comprising a roller over which and a holder 60 through which the tie passes.

2. A tie slide comprising a frame, a clamp thereon to secure it to the collar, a roller mounted in one end of the frame, and a tie holder in the other end of the frame. 65

3. A tie slide comprising a frame adapted to lie along the collar with a vertically sliding adjustable spring or yielding clamp on one side of the collar, and a tie holder through 70 which the tie passes on the other side.

4. A tie slide comprising a central open frame, with top and bottom pieces connected together at one end and carrying the roller at the other end of the slide, a holder formed on one end of the frame through which the 75 tie passes, and a collar clamp to hold the slide to the collar.

5. In a tie slide the combination of a frame detachably secured to the collar and comprising a roller over which and a holder 80 through which the tie passes, said collar clamp movably mounted on the frame.

6. A tie slide comprising a frame, a clamp thereon to secure it to the collar, a roller mounted in one end of the frame, and a tie 85 holder in the other end of the frame, said collar clamp movably mounted on the frame.

7. A tie slide comprising a frame adapted to lie along the collar with a clamp on one side of the collar, and a tie holder through 90 which the tie passes on the other side, said collar clamp movably mounted on the frame.

8. A tie slide comprising a central open frame, with top and bottom pieces connected together at one end and carrying the roller 95 at the other end of the slide, a holder formed on one end of the frame through which the tie passes, and a collar clamp to hold the slide to the collar, said collar clamp movably mounted on the frame.

9. A tie slide comprising a central open frame, with top and bottom pieces connected together at one end and carrying a connecting piece at the other end of the slide, a holder formed on one end of the frame 105 through which the tie passes, and a collar

clamp to hold the slide to the collar, said collar clamp movably mounted on the frame. through which the tie passes, and a collar clamp to hold the slide to the collar.

10. A tie slide comprising a central open frame, with top and bottom pieces connected together at one end and carrying a connecting piece at the other end of the slide, a holder formed on one end of the frame

WILLIAM TEMPLIN.
